FIG. 1

FIG. 2

FIG. 1 is a perspective view of the design looking toward a front corner of the design; and

FIG. 2 is a perspective view of the design looking toward a rear corner of the design.

The broken away portion shown in the drawing is to indicate indeterminate length.

Applicants' design is characterized by the combination of continuous side panels having slots therein, the substantially equal height of upholstery on the outside of the panels, the substantially equal height of the arms and back panels, and the sloping back inset from the rear and extending down only to the seat, all as shown.

We claim:

The ornamental design for a chair or similar article, as shown and described.
